APPARATUS FOR CASTING CONCRETE
WALLS

Charles Tyroler, Tuckahoe, N. Y.

Application September 26, 1946, Serial No. 699,365

11 Claims. (Cl. 25—1)

1

This invention relates to apparatus for casting concrete structures, and is more particularly directed to the casting of concrete walls.

In the art of concrete building, it is found advantageous to cast walls in a horizontal position and then to swing the same to a vertical position in their proper place in the building or structure to which they appertain. By so doing, all the advantageous features of horizontal casting are made available in the construction of walls, and said features include for instance simplicity of operation, economy in the forms or molds, accessibility of one face of the wall as an open face during the casting for hand finishing in the manner desired, and ease in placing within the form rods, stirrups, ties, nailing strips, and any other elements that it is desired to position therein. However, the horizontal casting of concrete walls presents difficulty of its own, as it is easily understood when it is considered that a concrete wall is an object of great size and weight, that it must be moved with care lest it become cracked, chipped or damaged, that its motion must be kept under strict control, and that in its rotation from the horizontal to the vertical position and vice versa it sweeps a great volume of space, while the clear space available on the job is often severely limited. Further it must be kept in mind that for economical reasons any casting method and apparatus cannot be excessively complicated or involve the use of expensive, non-reusable or easily damaged structures, or require too much time and labor to apply.

All apparatus of the prior art fail to overcome some or all of the difficulties above set forth. Accordingly, my present invention represents a novel and valuable contribution to the art inasmuch as it obviates all the shortcomings hitherto existing therein, and provides a method and apparatus which are of a simplicity, economy, and efficiency hitherto unattained. In describing my invention, I will particularly illustrate its application to a type of wall which is part of a building structure described and claimed in my copending application of even date herewith for Building structure. However I want it understood that I imply no limitation thereby, and that my invention may be applied to the casting of any type of concrete walls.

It is the general purpose of my invention to provide an apparatus for casting concrete walls in a horizontal position and then swinging the same to an upright position.

A more specific object is to provide such an apparatus which is particularly simple, economical, and efficient.

2

Another object is to provide such an apparatus wherein no power means are required to swing the wall upright.

A further object is to provide such an apparatus whereby the wall, when in its horizontal position, does not overhang the vertical plane to which it is to be swung.

A still further object is to provide such an apparatus wherein the swinging motion of the wall to its vertical position is under firm control and cannot acquire an objectionable speed.

A still further object is to provide such an apparatus which permits of bringing the wall to its final position in a single swinging motion.

A still further object is to provide such an apparatus for casting a wall and a section of roof together.

A still further object is to provide such an apparatus wherein all the structural elements, including the forms, are reusable.

A still further object is to provide such an apparatus whereby the stripping of the forms from the finished wall is practically instantaneous and automatic.

A still further object is to provide such an apparatus whereby no power means are required to return the concrete forms and the structure supporting the same to a horizontal position.

A still further object is to provide such an apparatus whereby the return motion of the forms and the structure supporting the same to the horizontal is under firm control and cannot acquire an objectionable speed.

A still further object is to provide such an apparatus which is disassemblable into individual spans for easy movement.

Other related and ancillary objects of my invention will clearly appear as the description proceeds.

40 In the drawings:

Fig. 1 is a schematic illustration of the method according to my invention, showing the casting apparatus and the wall in solid lines in the casting position and in broken lines in the final upright position.

Fig. 2 is a perspective view of a casting apparatus according to my invention shown in the horizontal position with the concrete poured therein, the concrete and the form being partially broken away to show the underlying supporting elements.

Fig. 3 is a transverse section of part of the same casting apparatus taken on the line 3.3 of Fig. 1.

55 Fig. 4 is a longitudinal section taken on the line 4.4 of Fig. 3.

Fig. 5 is a vertical section showing the wall in its final vertical position and the casting apparatus in its return swing to the horizontal position.

Fig. 6 is a perspective view of a modified apparatus suitable for casting a top section of wall solid with a roof section.

In the following description and claims, the word "wall" is to be construed as including a portion or section of wall, no matter how limited laterally or vertically. The word "concrete" when applied not to the fluid material but to a structure, is intended to include the reinforcement, if any.

Essentially, my method for casting concrete walls comprises the following steps. First, a rocker frame 10 is provided, by which is meant a supporting frame of any suitable construction, the top of which may have any convenient profile or shape, and the bottom of which has a portion 11—herein designated as the front portion—substantially shaped like an arc of circle subtending an angle of somewhat less than 90° (in the embodiment illustrated about 88°) or having any other suitable curved convex shape. The frame may rock, if actuated, and swing substantially from a horizontal position (shown in full lines in Fig. 1) to a vertical position (shown therein in broken lines). In this motion, the arc of circle or other curve of its bottom front portion 11 rollingly develops on the flat horizontal surface 12 which in fact will usually be a surface of concrete previously cast and set and has been thus indicated in the drawings. No connection or engagement is needed or contemplated in my method between the bottom of the rocker frame and said horizontal surface 12, other than a rolling frictional engagement. The center C of the circle to which are arc of circle 11, if it is an arc of circle, belongs, will be designated herein as the "center of rotation." It is the only point of the frame which describes a horizontal line, going from C to C¹ (Fig. 1) as the frame swings from the horizontal to the vertical position. All other points, obviously, described epicycloidal arcs. The perimeter of the arc 12 is equal to the segment AB.

One preferred embodiment of a rocker frame 10 is shown in detail in Figs. 2, 3, and 4. Such a frame embodies a number of longitudinal or rocker trusses 13 and a number of transverse trusses 14 which rigidly interconnect the longitudinal trusses 13. In the drawings there has been illustrated a frame comprising a minimum number of rocker trusses 13, namely two. Such an elementary frame may be designated as an "individual rocker span," and several rocker spans can be connected, disassemblably if so desired, by means of transverse trusses 14 to form a complete or multiple rocker frame for a complete wall. In practice, when a certain type of construction is to be erected a considerable number of times, as in the case of the building structure described and claimed in my aforementioned co-pending application, a number of individual rocker spans are built which are so dimensioned that by assembling part or all of them in various ways, different complete rocker frames can be provided for casting all the walls and partitions embodied in the construction in question. By disassembling the multiple rocker frames into individual rocker spans a greater mobility is also gained, as the frames themselves are usually of such dimensions and weight that they would be extremely hard to move about on the job. It is to be understood however that the expression

"rocker frame" as used in this description and in the appended claims, is intended to include both individual rocker spans and multiple frames.

Each rocker truss 13 has a rectangular portion 15, which is uppermost when the frame is vertical as seen in Fig. 1 and which will be called herein "rear portion," and a front portion the bottom of which is the curve 11. All of the trusses are preferably made of steel elements, angles, channels, strips, and the like, suitably interconnected in a rigid manner.

Upon the rocker frame there is attached a sectional form for the pouring of the concrete, which consists of elements open on top herein designated as "pans." Such pans run from front to rear like the pans 16 of Fig. 2, and have shapes related to the shape of the wall, later to be discussed fully. They are connected to the rocker frame on the one hand and to the concrete on the other in a manner to permit assembly and disassembly of the pans with respect to the rocker frame and stripping of the pans from the concrete once this latter has hardened and has been brought to its vertical position. To this end, within the pans there are positioned female tie elements. Male tie elements corresponding thereto are passed through suitable openings in the rocker frame and in the pans and are engaged to the female elements in such a manner as to be removable from the outside of the pans. An example of such ties is furnished by internally threaded sleeves and bolts engaging said sleeves, said bolts having their heads on the outside of the pans and therefore accessible at all times for removal. The ties must be sturdy enough to bind the concrete to the pans and rocker frame, once it has hardened, and to maintain the same in place during the swinging motion of the frame.

A preferred manner of mounting the ties is illustrated in detail in Fig. 3. In said figure, 17 designates one of the top elements of the transverse trusses 14, in the case illustrated a channel piece, on which there is superimposed a pan 16. This pan has a central deepest portion 18 providing a rib for the wall, and two shallower portions 19 at each side thereof. The pan is twice bent at right angles at each side thereof to provide wings 24 running from front to rear and bearing on the top elements such as 17. A number of female ties 20 are positioned vertically upon the pan 16. They are usually arranged in row, each row including one tie in each portion 18 of the pan, and/or, if so desired, one tie in each portion 19. Clearly the number and arrangement of such female ties 20 is a matter of judicious choice. The bottom pan 16 and the channel 17 have registering holes 21, 22 to permit of the passage therethrough of a male tie element 23 adapted threadingly to engage the female element 20. Male element 23 and female element 20 could be of any preferred structure, though in practice I have found that it is convenient to employ devices known in the trade for providing tie locking assemblies.

These consist of two sections of tightly wound wire, interconnected by straight longitudinal portions, and male elements suitably threaded to engage said sections. When a male threaded element is passed through the bores 21, 22 from the bottom to engage the bottom female section, the pans 16 are rigidly connected to the channels 17. After the concrete has hardened, the female elements 20 remain embedded therein, and thus tie the concrete to the pans 16 and to the rocker frame 10. After the wall has been

swung to its final vertical position, the male elements 23 are unscrewed and removed, the female elements 20 remain embedded in the concrete, and the rocker frame, pans, and concrete walls are no longer connected.

A set of secondary ties hereafter called "clips" is preferably provided between the outside of the pans 16 and the rocker frame 10. Such clips are completely clear of the concrete and only bind the pans to the frame. They need be only strong enough to overcome the adhesion between the pans and the concrete during the stripping of the former from the latter, as will be set forth hereinafter. A preferred embodiment of such clips and a preferred way of applying them is illustrated in Fig. 4. Clips or tongues 25, suitably bent, or any other similar elements, are attached, for instance by welding to the bottom of the wings 24 of the pans 16 or other pans and/or to other parts of the pans, if any, at the same level, and form therewith recesses engaging the top elements 17 of the transverse trusses 14. The point of attachment of the clips 25 to the pans is behind the elements 17, so that when the rocker frame 10 is vertical, gravity maintains the clips 25 in engagement with said elements 17. Thus, even after the bolts 23 have been removed and the concrete is not connected to the pans, these latter are still attached to the rocker frame 10.

The particular wall I have chosen to illustrate has a lower part (the front part when the rocker frame 10 is horizontal) which is flat on both faces and an upper part which is longitudinally recessed to provide vertical ribs. Accordingly pans 16 of the shape illustrated in Fig. 3 are used only to the rear of the rocker frame to define said upper ribbed part of the wall. For the bottom part of the wall pans 26 are used, which are illustrated in the forward portion of Fig. 2, and which are flat having no portion comparable to the portion 18. These pans have wings 27 similar to the wings 24 of the pans 16, and are mounted and connected in the same manner as the pans 16. They are also attached to the top elements of the transverse trusses which as a matter of design may be at a level different from that of the elements supporting the pans 16.

To complete the form there are provided a front plate 28, a rear plate 29, and two side plates 30, suitably bolted or otherwise detachably connected to the rocker frame 10.

The rocker frame is so proportioned, this being a matter of design only, that with the pans attached thereto its center of gravity is behind the center of rotation, that is it falls in the portion of the frame that has a substantially flat bottom. In this fashion the rocker frame normally rests on any flat surface in a horizontal position. However, the rocker frame is also so proportioned that the combined center of gravity of the frame itself, the pans, and the concrete when poured therein falls forwardly of the center of rotation, that is it overlies the circular bottom portion of the frame, so that the whole assembly with the concrete is unbalanced and tends to swing to the vertical, the curve 11 plus the form and thickness of the concrete subtend substantially 90°.

Means are provided to prevent the frame from swinging to the vertical position until it is deliberately released. Such means could be simple stops or blocks of any nature, but usually a rigging such as a block and tackle is preferred, as a rigging can be loosened slowly to guide the

frame during its upward swing. Such a rigging is illustrated generally at 31 in Fig. 1 and also in Fig. 6, but has been omitted from the remaining figures to avoid complicating them. A guiding action is not generally necessary, as the lever arm of the frame-pans-concrete assembly can be determined as a matter of judicious design, and can be made small enough in every case to prevent objectionable excessive acceleration of the assembly in the upward swing. However the use of a rigging avoids close figuring and is preferable.

The next steps consist in placing the reinforcement, ties, etc., pouring the concrete, tamping, leveling and finishing it with the usual technique of slab casting, and allowing it to set. The female ties aforementioned remain embedded in the concrete, and bind it firmly to the pans and rocker frame. Then the stops are removed, or the rigging is loosened, and the whole assembly is allowed to swing into a vertical position. Now the male ties are disengaged from the female ties and removed from the outside. Thus the hardened concrete wall is no longer bound to the rocker frame, and is bound to the pans only through surface adhesion. The rocker frame and the pans however are still connected by the aforementioned clips. Now the rocker frame, the center of gravity of which in the vertical position is above the center of rotation, is in unstable equilibrium, and tends to swing back to the horizontal. It is obstructed in so doing by the adhesion between the pans and the concrete. Therefore if the frame is suitably proportioned, that is if its center of gravity is sufficiently offset from the center of rotation, the frame will swing downwardly and in so doing will strip the pans from the concrete. Frame and pans then will be available immediately for casting another wall. Should however the stripping action not occur, as may conceivably happen in some exceptional cases, it will suffice to remove the clips, whereupon the frame alone will swing to the horizontal and the pans will be left clinging to the wall, to be stripped therefrom individually in the usual manner.

In view of the great weight of the frame, it is often desirable to provide control and brake means preventing the frame from acquiring an excessive speed in its downward swing. These means could be in the form of an appropriate rigging. A preferred embodiment is that illustrated in Fig. 5. Therein an arm 32 is pivoted at 33 to the frame 10, and has a foot 34 embodying a slide, as shown, or a roller. As the frame 10 swings downwardly, the angle between said arm 32 and said frame increases. Said angle is controlled by a cable 35 or the like attached to the arm 32 at 36, passing over a pulley 37 attached to the frame 10, and being controlled at the other end 38. The cable 35 is paid out slowly enough to maintain the pivotal motion of the arm 32 about 33, and hence the downward swing of the frame 10, within the speed limits desired.

The operations which take place subsequently, after the wall has been placed in its final position, to tie the wall to the rest of the building, form no part of my present invention, and therefore need not be described herein. An example of a building structure embodying walls that can be conveniently cast in the manner herein described is given in my aforementioned copending application. It is to be emphasized that walls can be cast by means of this invention which do not embody a flat and a ribbed portion. Also that other

details in the walls can be provided by suitably designing the pans or by using additional devices of a type known in the art. For instance, openings for windows or the like, and air passages or bores for air ducts through the ribs of the wall can be formed by placing within the pans suitable mask to prevent the access of concrete to the volume that it is desired to keep open. Likewise additional ties can be embedded in the wall to furnish a binding connection to other elements of the building structure, and wooden nailing strips and the like, as well as elements of electrical conduits, can be placed in the forms so that they will be held in the concrete near the surface thereof to provide a foundation for the attachment of interior panels, window jamb, fixtures and so forth.

Another embodiment of my invention which is illustrated in Fig. 6 consists of an apparatus by means of which, following the same steps described above in the case of a section of wall, it is possible to cast in a horizontal position and then swing to their proper position in a building structure a wall or section of wall and a section of roof together. The apparatus embodies a rocker frame 40, upon which there is mounted a sectional form generally indicated in 41, which will consist of pans and side plates and end plates analogous to those hereinbefore described in the case of the first embodiment of my invention. In Fig. 6 the side plate facing the observer has been removed. It is seen therein that the particular type of wall illustrated is of the same type as the wall illustrated in connection with the first embodiment. However, as previously stated, any other type of wall could be cast by the same method by suitably designing the forms, and whenever desired, the rocker frame. The forms used in connection with the embodiment of Fig. 6 comprises a section 42 wherein a conveniently sloping portion 43 of a roof can be cast solid with the wall or section of wall 44. A block and tackle rigging 45 is used herein to control the swing of the rocker frame 40 to the vertical position, and all the other elements and procedures described in the case of the first embodiment are repeated herein.

The advantages inherent in casting the roof solid with the walls when these latter are in horizontal position and then swinging the same together to their final position in the building structure, are too obvious to need much elaboration. It is well known that the building of roofs, as heretofore carried out embodies the cumbersome procedure of carrying the building materials, and the materials of the forms, if the roof is made of concrete, to the top of the erected walls and assembling said elements in position therein. By the application of my invention there is no more labor involved in casting the roof than there is in casting a horizontal floor slab located at or near the ground level. The whole construction job is thereby rendered simpler, quicker and more economical, as well as generally sounder from an engineering viewpoint.

It is seen therefore that I have provided a method and an apparatus for the casting of concrete walls which completely achieve the objects set forth at the beginning of this specification. I have described a preferred embodiment of my invention for purposes of illustration. However, I want it understood that this implies no limitation, and that numerous changes, modifications and adaptations may be made therein without departing from the spirit of the invention or ex-

ceeding the scope of the claims. I also want it understood that the word "wall" as used in the foregoing description and claims has been construed to include either a complete wall or a portion or section of wall as the case may be, and to include a wall or portion of wall solid with or separate from a portion of roof, as the case may be, unless otherwise specifically set forth.

I claim:

1. An apparatus of the character described for casting concrete walls, comprising a frame normally self supported in a horizontal plane and having a portion shaped like an end curved sector, a form supported thereby for pouring a concrete wall in a horizontal position thereon, the gravitational load on said frame when said form is filled with concrete being so distributed as to urge said frame to swing along the curved sector thereof to a vertical position, and means for maintaining said frame horizontal until the concrete poured in said form has hardened.

2. An apparatus of the character described for casting concrete walls, comprising a frame having a bottom consisting of a flat portion and a rounded portion, said frame being normally stable in a horizontal position; a form supported by said frame for pouring a concrete wall in a horizontal position, the combined center of gravity of said frame and the load supported thereby when said form is filled with concrete falling above said rounded portion of the frame bottom, whereby said frame together with said form and wall tends to swing along the rounded portion thereof to a vertical position; and means for maintaining said frame horizontal until the concrete has hardened.

3. An apparatus of the character described for casting concrete walls, comprising a frame having a bottom consisting of a flat portion and a substantially circular arc portion, said frame being normally stable in a horizontal position; a form supported by said frame for pouring a concrete wall in a horizontal position, the combined center of gravity of said frame and the load supported thereby when said form is filled with concrete falling in the concrete above said circular arc portion of the frame bottom, whereby said frame together with said form and wall tends to swing along the circular arc portion thereof to a vertical position and is stable therein; and means for maintaining said frame horizontal until the concrete has hardened.

4. An apparatus of the character described for casting concrete walls, comprising a frame having a bottom consisting of a flat portion and a rounded portion, the center of gravity of said frame falling above said flat portion whereby said frame is normally stable in a horizontal position; a form supported by said frame for pouring a concrete wall in a horizontal position, the combined center of gravity of said frame and the load supported thereby when said form is filled with concrete falling above said rounded portion of the frame bottom; means for removably connecting said frame to the concrete, whereby when said means are operative said frame together with said form and wall tends to swing as a body along the rounded portion thereof to a vertical position; and thereafter when said means are rendered inoperative said frame tends to swing back to its horizontal position; and means for maintaining said frame horizontal until the concrete has hardened.

5. An apparatus of the character described for pouring concrete walls according to claim 4

wherein the means for removably connecting the frame to the concrete comprise tie elements so located in said form as to become embedded in the concrete poured therein, and means for removably connecting said frame to said tie elements.

6. An apparatus of the character described for pouring concrete walls according to claim 4, wherein the means for removably connecting the frame to the concrete comprise female screw elements positioned in the form so as to become embedded in the concrete when this latter is poured therein, and male screw elements passing through registering openings in said frame and form to engage said female elements, thereby clamping said frame, form and concrete together.

7. An apparatus of the character described for pouring concrete walls according to claim 4, wherein separate means are provided for removably connecting the form directly to the frame.

8. An apparatus of the character described for casting concrete walls, comprising a flat bottomed portion extending along substantially the greatest part of its length and an end frame having a portion shaped like a curved sector, a form supported thereby for pouring a concrete wall in a horizontal position, the gravitational load on said frame when said form is filled with concrete being so distributed as to urge said frame to swing along the curved sector thereof to a vertical position, means for maintaining said frame horizontal until the concrete poured in said frame has hardened, and means for controlling the swing of said frame to a vertical position to maintain the speed of the same within desired limits.

9. An apparatus of the character described for casting concrete walls, comprising a frame having a bottom consisting of a flat portion and a rounded portion, the center of gravity of said frame falling above said flat portion whereby said frame is normally stable in a horizontal position; a form supported by said frame for pouring a concrete wall in a horizontal position, the combined center of gravity of said frame and the load supported thereby when said form is filled with concrete falling above said rounded portion of the frame bottom; means for removably connecting said frame to the concrete, whereby when said means are operative said frame together with said form and wall tends to swing along the rounded portion thereof as a body to a vertical position; and thereafter when said means are rendered inoperative said frame tends to swing back to its horizontal position; means for maintaining said frame horizontal until the concrete has hardened; and means for controlling the swing of the frame from its vertical back to its horizontal position to maintain the speed of the same within desired limits.

10. An apparatus of the character described for casting concrete walls, comprising a rockable frame; a sectional form supported by said frame

for pouring a concrete wall in a horizontal position; said frame having a base consisting of a flat portion and a rounded portion and adapted to rock along the rounded portion thereof, said frame with said form being stable in a horizontal plane said frame with said form and wall being stable in a vertical position and assuming the same by gravity unless restrained; said form embodying pans defining one face of the wall, and plates defining the top, bottom, and edges of the wall, the other face of the wall being an open horizontal surface when the wall is being cast; and means for attaching said pans and plates to said frame.

11. An apparatus of the character described for casting concrete walls comprising a rockable frame; a form for pouring a concrete wall in a horizontal position; means for removably connecting said frame to the concrete, said frame embodying a number of parallel trusses each having a flat-bottomed rear portion and a forward portion shaped substantially like an arm of a sector, circular sector and a number of transverse elements rigidly and dismountably connecting said trusses, whereby said frame is rockable between a horizontal and a vertical position by swinging about the centers of said circular sectors of the trusses embodied in said frame, the combined center of gravity of said frame with the form it supports being positioned behind said sector centers and shifting when said form is filled with concrete to a position forwardly enough of said sector center to swing said frame thereabout to a vertical position, unless restrained; means for maintaining said frame horizontal until the concrete has set; said form embodying pans defining one face of the wall and plates defining the top, bottom, and edges of the wall; means for removably attaching said pans and plates directly to elements of said frame; means for controlling the swing of said frame from a horizontal to a vertical position to contain the speed thereof within desired limits; said frame when in its vertical position and when detached from the concrete swinging back to its horizontal position; and means for controlling such back-swing to contain the speed thereof within desired limits.
